TYPEWRITER ERASER

John George Ziegler and Agda W. Carlson,
Rawlins, Wyo.

Application October 6, 1933, Serial No. 692,540

9 Claims. (Cl. 120—36)

This invention relates to an improved typewriter eraser and more particularly to certain refinements in the device shown in Patent No. 1,788,658, issued to Chris C. Carlson January 13, 1931.

The invention seeks, especially, to provide a device embodying a rotary abrading element wherein only one hand of the operator will be required to hold the device in proper position for making an erasure and at the same time permit rotation of the abrading element to effect the erasure.

The invention seeks, as a further object, to provide a device embodying a gear for rotating the abrading element and wherein the gear will be conveniently exposed, for engagement by the thumb of the hand for turning the gear and, consequently, rotating said element.

And the invention seeks, as a still further object, to provide a device wherein the abrading element may be conveniently renewed.

With the foregoing and other objects in view, the invention consists in certain novel details of construction and combinations of parts herein-after fully described and claimed, it being understood that various modifications may be resorted to within the scope of the appended claims without departing from the spirit or sacrificing any of the advantages of the invention.

In the drawing, Figure 1 is a side elevation of my improved device, approximately actual size, Fig. 2 is an enlarged elevation, one side wall of the casing being removed,

Fig. 3 is a vertical sectional view on the line 3—3 of Fig. 2,

Fig. 4 is a vertical sectional view on the line 4—4 of Fig. 2,

Fig. 5 is a transverse sectional view on the line 5—5 of Fig. 2.

In carrying the invention into effect, we employ an oblong casing preferably of "bakelite", although metal or other suitable material may be employed and, as best seen in Figs. 2 and 5 of the drawing, this casing includes a side wall 10,

lateral walls 11 and 12, an end wall 13 and an opposite side wall 14, the walls 11, 12 and 13 being integral with the side wall 10. The casing is open at its forward end and, as will be observed, the end wall 13 at the rear end of the casing is somewhat thicker than the walls 11 and 12 and is cut away to provide a recess 15 adapted to receive a finger while opposite the recess, said wall is flanged at its inner side to provide upstanding stops 15' defining a socket 16.

Integral with the side wall 10 is a short flange

or web 17 extending in spaced parallel relation to the wall 11 and likewise integral with the wall 10 is a more or less triangular shaped web 18 the lower edge of which constitutes a stop or abutment. These webs cooperate with the walls 11 and 12 to define a pair of guide slots 19. As best seen in Fig. 2, the wall 11 is notched to provide an opening 20 at the adjacent edge of the casing while, as shown in Fig. 1, the side wall 14 is provided with a lateral flange 21 to snugly fit in said notch. Opposite the opening 20, the wall 12 is preferably serrated, as indicated at 22.

Fixed to the wall 10, as best seen in Fig. 5, is a stud 23 located medially of the casing, near the open end thereof, and suitably fixed to said wall, medially with respect to the opening 20, as best seen in Fig. 4, is a like stud 24. Engaged in the free ends of said studs are screws 25 removably securing the side wall 14 in position.

Removably mounted upon the stud 23 is an abrasive unit including a hub sleeve 26 and pressed over one end of said sleeve is a gear 27 tightly engaged with the sleeve. Snugly but removably surrounding the sleeve is a circular abrasive element 28 which abuts the gear 27 and screwed over the free end of the sleeve is a preferably split circular nut 29 clamping the element 28 between said nut and the gear 27. The abrasive element 28 is of rubber of the character usually employed for circular typewriter erasers and will be tightly held between the gear 27 and nut 29 to turn with the sleeve. When, however, said element becomes worn, the nut may be readily removed and a new element substituted therefor. The nut 29 is preferably resilient and by splitting the nut, it is permitted to grip the threads at the free ends of the sleeve so that the nut is thus frictionally held against loosening. At its outer circumference, the nut is preferably milled to facilitate the manual removal thereof.

Removably fitting on the stud 24 is a compound gear unit including a hub sleeve 30 and pressed over the ends of said sleeve to tightly engage therewith are gears 31 and 32 of like diameter. The gear 31 meshes with the gear 27. The gear 32, however, is an idler gear. Both gears project through the opening 20 of the casing and two gears are employed so that the peripheries thereof may be conveniently engaged by the thumb of the operator for turning the gear unit and, consequently, rotating the abrasive element 28. The teeth at the peripheries of the gears will afford adequate purchase for the thumb of the operator and, by using two gears, possibility of injury or

discomfort, incident to turning the gear unit, will be avoided.

Slidable in the casing is a shield including a front cross bar 33, side bars 34 and 35 and a rear cross bar 36. The shield is preferably formed of a strip of suitable resilient sheet metal bent to proper shape, and, as shown in Fig. 2, the overlapping ends of said strip provide the cross bar 36. Extending through said ends is a stud 37 securing the ends together. The side bars 34 and 35 of the shield are slidably received in the guide slots 19 of the casing, the side bar 34 being cut away at opposite edges thereof, as seen in Fig. 3, and provided with a reduced neck 38 which is freely accommodated between the gears 31 and 32 of the gear unit. The end bar 32 of the shield is formed with a bowed portion or saddle 39 adapted to fit the circumference of an ordinary typewriter platen and extending longitudinally of said 20 saddle is a slot 40 adapted to freely accommodate the abrasive element 28 therethrough. Fitting at one end in the socket 16 and engaging at its opposite end over the stud 37 is a spring 41 projecting the shield forwardly. Forward movement of the shield is limited by the engagement of the cross bar 36 thereof with the stop formed by the rear end of the web 18 while inward or rearward movement of the shield will be limited by the engagement of the cross bar 33 with the 30 stops 15'.

In use, the edges of the casing are grasped between the thumb and fingers, the index finger preferably resting in the recess 15 of the end wall 13 of the casing. The saddle is then placed 35 against the paper on the typewriter platen and the slot 40 positioned over the letter to be erased. By then pressing forwardly on the casing, the shield is moved inwardly until the abrasive element 28 is brought into engagement with the 40 paper when, by rotating the gears 31 and 32 with the thumb, the abrasive element may be rotated for erasing the desired letter. We accordingly provide a device which may be operated with ease and facility and attention is directed to the fact 45 that the portions of the cross bar 33 of the shield at opposite sides of the slot 40 will protect letters of a word, for instance, at opposite sides of the letter which it is desired to erase so that smudging will be obviated. Furthermore, as will be seen, 50 the side wall 14 of the casing may be readily removed, when the parts may be readily lifted out for renewing the abrasive element in the manner previously described.

Having thus described the invention, we claim:

1. An eraser including a casing, a rotatable abrading element projecting from the casing, means for rotating said element including spaced gears having portions thereof projecting from the casing and adapted to be manually engaged 55 for turning the gears and rotating said element, and a yieldably supported shield slidably mounted in the casing between said gears and having one end thereof extended over the abrading element and provided with a slot adapted to receive said element.

2. An eraser including a casing, a sleeve, a gear carried by the sleeve, an abrading element mounted on the sleeve, means carried by the sleeve and clamping said element between said 60 means and said gear, means journaling said sleeve and supporting said element to project from the casing, spaced gears exposed at the exterior of the casing, one of which meshes with said first-mentioned gear, and a yieldably supported shield 75 having a portion thereof slidably mounted in the

casing between said spaced gears and having its outer end extended over the abrading element and slotted to receive said element.

3. An eraser including a casing, a rotatable gear, an abrading element mounted to turn with said gear and projecting from the casing, a sleeve, spaced gears fixed to said sleeve, one of which meshes with said first-mentioned gear, and means journaling the sleeve, said spaced gears being exposed externally of the casing and a reciprocating shield yieldably supported in the casing and having a reduced portion slidably mounted between the spaced gears and its outer end extending over the abrading element and provided with a slot adapted to receive said element. 80

4. An eraser including a casing having spaced walls, webs within the casing and cooperating with said walls to define guide slots, a rotatable abrading element exposed at one end of the casing, means for rotating said element including spaced gears exposed at an edge of the casing and adapted to be manually engaged for turning said gears and rotating said element, a shield having side bars slidable in said slots and provided with a reduced portion fitted between said spaced gears, and yieldable means normally holding the shield projected at said end of the casing, the shield being compressible over the exposed portion of said element. 85

5. An eraser including a casing, a rotating abrading element projecting from the casing, means for rotating said element including a gear having a portion thereof exposed at the exterior of the casing, a reciprocating shield slidably mounted in the casing and movable across said gear, spaced stops on the bottom of the casing defining a socket, a spring seated in the socket and bearing against the lower end of the shield, and a stop disposed within the casing and coacting with the lower end of the shield for limiting the outward movement of said shield. 100

6. An eraser including a casing, a rotating abrading element projecting from the casing, means for rotating said element including a gear having a portion thereof exposed at the exterior of the casing, a reciprocating shield slidably mounted within the casing and movable across one side of the gear, the upper end of the shield extending over the abrading element and having a slot therein to receive said element, spaced stops on the bottom of the casing for limiting the inward movement of the shield and defining a socket, a stop spaced from the first-mentioned stops for limiting the outward movement of the 110 shield, and a spring fitted in the socket and bearing against the shield for normally holding the lower end of the shield in engagement with the last-mentioned stop. 115

7. An eraser including a casing, a rotatable abrading element projecting from the casing, a gear carried by said abrading element, spaced gears, one of which meshes with the gear on the abrading element, said spaced gears having a portion of their peripheral edges normally exposed at the exterior of the casing, a reciprocating shield slidably mounted in the casing and having one side thereof provided with a reduced portion fitting between the spaced gears and its outer end extending over the abrading element 130 and slotted to receive the same, stops secured to the bottom of the casing for limiting the inward movement of the shield, said stops defining an intermediate socket, a stop spaced from the first-mentioned stops for limiting the outward move- 140

75 150

- ment of the shield, and a spring seated in the socket and bearing against the lower end of the shield for normally and yieldably holding the bottom of the shield in engagement with the 5 last-mentioned stop.
8. An eraser including a casing, an abrading element projecting from the casing, a gear carried by the abrading element, spaced gears, one of which meshes with the gear on the abrading 10 element, said spaced gears having a portion of their peripheral edges normally projecting beyond the casing, a yieldably supported substantially rectangular shield slidably mounted within the casing and having one of its side walls cut 15 away to provide a reduced portion fitting between the spaced gears and its upper end slotted to accommodate the abrading element, means for limiting the inward sliding movement of the shield, and other means for limiting the outward 20 sliding movement of said shield.
9. An eraser including a casing, an abrading element rotatably mounted in said casing and projecting from an end thereof, an actuating element rotatably mounted in said casing and having a driving disk and also having a finger engaging disk projecting through a side wall of the casing, means for transmitting rotary motion from the driving disk to the abrading element when the actuating element is rotated, and a yieldably supported shield slidably mounted in said casing and having a portion extending between the disks of the actuating element, the shield having its outer portion extending over the abrading element and formed with a slot to permit passage of the abrading element through the shield when the shield is forced inwardly. 80
